INVENTOR

UNITED STATES PATENT OFFICE

96,205

DESIGN FOR A LADY'S SLIPPER

Abraham J. Siegler, Brooklyn, N. Y.

Application May 1, 1935, Serial No. 56,636

Term of patent 3½ years

To all whom it may concern:

Be it known that I, Abraham J. Siegler, a citizen of the United States of America, residing in Brooklyn, county of Kings, and State of New York, have invented a new, original, and ornamental Design for a Lady's Slipper, of which the following is a specification, reference being had to the accompanying drawing, forming part thereof, wherein,

The vertical lines around the instep portion of the slipper represent a two-tone lamb skin collar.

I claim:

The ornamental design for a lady's slipper, substantially as shown and described.

ABRAHAM J. SIEGLER.
